US00D912260S

(12) **United States Design Patent** (10) **Patent No.:** **US D912,260 S**
Okuda et al. (45) **Date of Patent:** **** Mar. 2, 2021**

(54) **SHEET PREPARATION TO BE APPLIED ON A HUMAN BODY**

(71) Applicant: **KOBAYASHI PHARMACEUTICAL CO., LTD.**, Osaka (JP)

(72) Inventors: **Naoyuki Okuda**, Ehime (JP); **Hiroki Horimoto**, Osaka (JP); **Tatsuki Koeda**, Osaka (JP); **Akira Nagamatsu**, Osaka (JP)

(73) Assignee: **KOBAYASHI PHARMACEUTICAL CO., LTD.**, Osaka (JP)

(**) Term: **15 Years**

(21) Appl. No.: **29/675,075**

(22) Filed: **Dec. 28, 2018**

(30) **Foreign Application Priority Data**

Jun. 29, 2018 (JP) 2018-014513

(51) **LOC (13) Cl.** **24-04**

CLAIM

The ornamental design for a sheet preparation to be applied on a human body, as shown and described.

DESCRIPTION

FIG. 1 is a front perspective view of a sheet preparation to be applied on a human body showing our new design;

FIG. 2 is a front view thereof;

FIG. 3 is a top view thereof;

FIG. 4 is a right side view thereof;

FIG. 5 is a left side view thereof;

FIG. 6 is a rear view thereof; and,

FIG. 7 is a bottom view thereof.

1 Claim, 7 Drawing Sheets
